CLAIM

The ornamental design for a duffel bag for a stroller or the like, as shown and described.

DESCRIPTION

FIG. 1 is a front elevational view of a duffel bag for a stroller or the like showing my new design;

FIG. 2 is a side elevational view thereof, the undisclosed side being a mirror image;

FIG. 3 is a rear elevational view thereof;

FIG. 4 is a bottom plan view thereof;

FIG. 5 is a top plan view thereof; and

FIG. 6 is a side elevational view thereof, attached to a stroller, the broken lines shown for illustrative purposes only, forming no part of the claimed design.

FIG. 1

FIG. 2

FIG. 3

FIG. 4

FIG. 5

FIG. 6
